(57) **CLAIM**

The ornamental design for a charger holder, as shown and described.

DESCRIPTION

FIG. 1 is a perspective view of a charger holder showing our new design.

FIG. 2 is a side view thereof.

FIG. 3 is another side view thereof, from the opposite side shown in FIG. 2.

FIG. 4 is another side view thereof.

FIG. 5 is another side view thereof, from the opposite side shown in FIG. 4.

FIG. 6 is a top view thereof; and,

FIG. 7 is a bottom view thereof.

The dashed lines show portions of the charger holder that form no part of the claimed design. The dashed lines form the boundaries of surface areas of the charger holder that are not part of the claimed design and any area bound entirely by dashed lines is a portion of the charger holder that forms no part of the claimed design.

The dot-dash broken lines form no part of the claimed design.
